(57) **CLAIM**

The ornamental design for a golf club grip, as shown and described.

DESCRIPTION

FIG. 1 is a bottom perspective view of a first embodiment of a golf club grip;

FIG. 2 is a top perspective view of the golf club grip of FIG. 1;

FIG. 3 is a front view of the golf club grip of FIG. 1;

FIG. 4 is a rear view of the golf club grip of FIG. 1;

FIG. 5 is a toe side view of the golf club grip of FIG. 1;

FIG. 6 is a heel side view of the golf club grip of FIG. 1;

FIG. 7 is a top view of the golf club grip of FIG. 1;

FIG. 8 is a bottom view of the golf club grip of FIG. 1;

FIG. 9 is a bottom perspective view of a second embodiment of a golf club grip;

FIG. 10 is a top perspective view of the golf club grip of FIG. 9;

FIG. 11 is a front view of the golf club grip of FIG. 9;

FIG. 12 is a rear view of the golf club grip of FIG. 9;

FIG. 13 is a toe side view of the golf club grip of FIG. 9;

FIG. 14 is a heel side view of the golf club grip of FIG. 9;

FIG. 15 is a top view of the golf club grip of FIG. 9;

FIG. 16 is a bottom view of the golf club grip of FIG. 9;

FIG. 17 is a bottom perspective view of a third embodiment of a golf club grip;

FIG. 18 is a top perspective view of the golf club grip of FIG. 17;

FIG. 19 is a front view of the golf club grip of FIG. 17;

FIG. 20 is a rear view of the golf club grip of FIG. 17;

FIG. 21 is a toe side view of the golf club grip of FIG. 17;

FIG. 22 is a heel side view of the golf club grip of FIG. 17;

FIG. 23 is a top view of the golf club grip of FIG. 17;

FIG. 24 is a bottom view of the golf club grip of FIG. 17;

FIG. 25 is a bottom perspective view of a fourth embodiment of a golf club grip;

FIG. 26 is a top perspective view of the golf club grip of FIG. 25;

FIG. 27 is a front view of the golf club grip of FIG. 25;

FIG. 28 is a rear view of the golf club grip of FIG. 25;

FIG. 29 is a toe side view of the golf club grip of FIG. 25;

FIG. 30 is a heel side view of the golf club grip of FIG. 25;

FIG. 31 is a top view of the golf club grip of FIG. 25; and,

FIG. 32 is a bottom view of the golf club grip of FIG. 25. The broken lines shown on the drawings form no part of the claimed design.
